POCKET COMB AND BRUSH

Louis H. Bear, Chicago, Ill.

Application November 3, 1932. Serial No. 640,987

4 Claims. (Cl. 132—86)

This invention relates to improvements in pocket combs and brushes. One object is to provide a comb and brush mounted in a single case, the comb being slidably mounted in the median line of the case and adapted to fit snugly within the same when not in use, the brush being of a rotary type and mounted to prongs extending outwardly or downwardly from one edge of the case, the arrangement being such that the comb or the brush may be used at one time or both may be used at the same time if desired.

5 A further object is to provide a pocket comb and brush of simple construction, inexpensive to manufacture and that is durable and efficient in use.

10 With the foregoing and other objects in view the invention consists in the combination and arrangement of parts to be hereinafter fully described, pointed out in the claims and illustrated 20 in the accompanying drawing which forms a part of this application for patent and in which—

Fig. 1 is a view of the pocket comb and brush in side elevation, the comb being extended for use.

25 Fig. 2 is a similar view with the comb retracted.

Fig. 3 is an end view of Fig. 2, and is taken on the line 3—3 thereof.

30 Fig. 4 is a vertical cross sectional view taken on the line 4—4 of Fig. 1.

Like reference characters denote corresponding parts throughout the several views.

The reference numeral 1 denotes the case which is formed with the median cavity 3 extending 35 from a point 2 adjacent one end of the case lengthwise to the opposite and open end, said cavity being formed along one edge with the enlarged or widened portion 4 and provided adjacent the open end of the case with a stop projection 5.

40 Slidably mounted in said cavity is the comb 6 formed at one end with the heel 7 for abutment with the said stop and along one longitudinal edge with the lateral flanges 8 that seat in the 45 said cavity portion 4, said comb being formed,

further, at one end with the spur 9 that serves as a fingernail cleaner. The comb is manually withdrawn from or telescoped into the case cavity by means of said spur also and in the extended position shown in Fig. 1 the case may be 60 held in one hand and one finger of that hand applied to the back or flanged edge of the comb to exert such pressure thereupon as may be desired to cause it to comb to a greater or less depth in thick hair or to pleasantly rub or scratch 65 the scalp in very thin hair.

Depending from opposite ends of the case are the two parallel prongs 10 formed with tiny recesses 13 to permit mounting of the shaft 11 of the rotary brush 12. Ordinarily the comb or 70 brush alone is used, although the fact that the teeth of the comb are positioned adjacent the brush with relation to the back of the comb it is possible and sometimes desirable to comb and brush the head at the same time. Passing the 75 comb and brush over the head with the bristles of the brush in contact with the hair will cause rotation of the brush through friction.

What is claimed is:—

1. In a comb and brush combination, a case 80 formed with a median line cavity extending longitudinally from one closed end to the opposite open end, a comb slidably arranged in said cavity, and a rotary brush carried by said case.

2. In a comb and brush combination, a case 85 formed with a median line cavity extending from one closed end to the opposite open end of the case and formed with an enlarged portion, a comb slidably arranged in said cavity and formed with flanges disposed in said enlargement, and a 90 brush carried by said case.

3. In a comb and brush combination, a case, a comb telescopically carried thereby, and a rotary brush carried by said case.

4. In a comb and brush combination, a case 95 formed with prongs, a comb telescopically mounted to said case, and a rotary brush operatively carried by said prongs.

LOUIS H. BEAR.
